UNITED STATES PATENT OFFICE.

PULASKI B. BROUGHTON, OF AUSTIN, MINNESOTA.

BRICK-KILN.

SPECIFICATION forming part of Letters Patent No. 434,058, dated August 12, 1890.

Application filed August 28, 1889. Serial No. 322,220. (No model.)

To all whom it may concern:

Be it known that I, PULASKI B. BROUGHTON, a citizen of the United States, residing at Austin, in the county of Mower and State 5 of Minnesota, have invented a new and useful Brick-Kiln, of which the following is a specification.

This invention relates to brick-kilns; and it has for its object to provide a structure of 10 this class which shall be simple and easily constructed and in which brick may be dried and burned more quickly and in a more perfect manner than in kilns of the construction heretofore generally employed.

15 With these ends in view the invention consists in the improved detailed construction of a kiln, which will be hereinafter fully described, and particularly pointed out in the claims.

20 In the drawings hereto annexed, Figure 1 is a perspective view of my improved kiln. Fig. 2 is a longitudinal vertical sectional view. Fig. 3 is a vertical transverse sectional view.

Like numerals of reference indicate like 25 parts in all the figures.

11 designate the side walls, and 22 the end walls, of my improved kiln.

30 3 designates the floor of the kiln, which is provided with a central longitudinal flue or ditch 4 and with a longitudinal flue or ditch 5 on each side between the said central flue and the side walls.

35 66 designate the furnaces, any desired number of which may be built or constructed transversely under each of the side walls 1. Located under the furnaces 6, and separated therefrom by the grates 7, are the ash-pits 8, which, as well as the furnace, are provided at their outer ends with doors 9 of ordinary 40 construction. The inner ends of the furnaces open directly into the kiln, which is provided with back walls or fire-walls 10, erected a short distance from and parallel to the side walls 1 and extending nearly to the 45 roof 11 of the kiln. The ash-pits 8 are connected by upwardly-inclined flues 12 with the longitudinal flues 5 in the floor of the kiln, and at the outer ends of the said flues are arranged dampers 13, which when closed cut 50 off communication between the ash-pits and the flues 5.

A series of chimneys 14 are constructed

centrally on a longitudinal line of the kiln, said chimneys extending from the central flue 4 upwardly through the roof of the kiln. 55 The said chimneys are provided at their lower ends with openings 15, through which the products of combustion may pass from the flue 4 into the said chimneys. At their upper ends the said chimneys are provided 60 with valves or dampers 16, having handles 17, by means of which they may be conveniently manipulated so as to regulate the draft.

The end walls of the kiln are provided with suitably-constructed doors 18, through which 65 access may be had to the interior, and in the arched roof of the kiln are placed a series of small ventilators 24.

To brace and strengthen the kiln, I erect adjacent to the outer sides of the side walls 70 a series of vertical posts 19, the upper ends of which are connected by braces 20, extending transversely across the top of the kiln.

In operation the bricks which are to be dried and burned are piled in the usual manner upon the floor of the kiln, which, as will be noticed, is solid in contradistinction to the perforated floor usually employed in down-draft-kilns, and which in several respects is undesirable. After piling the brick and closing the doors of the kiln, fires are first started in the ash-pits, the dampers 13 at the inner ends of which are temporarily opened, so as to cause an upward draft through the flues 12 and 5 and through the brick piled in the 85 kiln. The products of combustion after passing upwardly through the kiln will escape through the small ventilators 24, that are placed in the arched roof, making a perfect updraft for carrying off the moisture while 90 the brick are being dried. This upward draft will carry off the moisture from the bricks instead of allowing it to condense and become deposited upon the brick and floor of the kiln, as is generally the case in downdraft-kilns when the fire is first started. After the 95 brick has been dried and most or all of the moisture evaporated, the dampers 13 and ventilators 24 are closed and fires are started in the furnaces proper. The draft will now be 100 upward through the spaces 21, between the fire-walls 10 and the side walls 1, and thence downwardly through the brick and to the central flue 4, from whence the products of

combustion will escape through the chimneys. It will be seen that the back wall or fire-wall 10 serves to condense the fires from the several furnaces into a solid sheet, which will 5 strike the brick piled in the kiln evenly, thus causing the brick to be burned very uniformly throughout; nor is the heat lost entirely after passing once down through the brick, as is the case in downdraft-furnaces having 10 perforated floors, inasmuch as the passage of the products of combustion upwardly through the chimneys converts the latter into very powerful radiators, which greatly assist not only in lessening the time required to burn a kiln 15 of brick, but also in securing a more uniform and marketable product than heretofore. The draft may at all times be regulated by means of the dampers 16 in the upper ends of the chimneys, and it will be seen that by closing 20 the said dampers the heat may be confined in the kilns and the latter allowed to cool slowly and gradually.

Having thus described my invention, what I claim as new, and desire to secure by Letters Patent, is—

1. A brick-kiln consisting of the structure having the side and the end walls and the roof, the longitudinal ditches in the floor of said structure, the furnaces constructed transversely in the side walls and having open inner ends opening directly into the kiln, the fire-walls arranged parallel to and at a short distance from the side walls, the grates separating the furnaces from the ash-pits, the flues connecting the latter with the longitudinal flues or ditches in the floor of the kiln at the sides of the latter, the dampers at the outer ends of said connecting-flues, and the ventilators in the arched roof of the kiln, substantially as set forth.

2. A brick-kiln consisting of the structure having the side and the end walls and the roof, the flues or ditches formed longitudinally in the floor, the furnaces constructed 45 transversely in the side walls, the fire-walls arranged parallel to and at a distance from the side walls, the flues connecting the ash-pits with the longitudinal side flues in the floor of the kiln, the dampers at the outer 50 ends of said connecting flues, the chimneys

extending upwardly from the central flue in the floor of the kiln and having openings at their lower ends for the admission of products of combustion, and the dampers arranged in the upper ends of said chimneys, substantially as herein set forth.

3. A brick-kiln having the longitudinal flues or ditches formed in the floor thereof, the chimneys rising from the central flue and having openings at their lower ends for the admission of products of combustion, the furnaces constructed transversely in the side walls of the kiln and having open inner ends, the fire-walls arranged parallel to and at a short distance from the side walls of the kiln, 65 flues connecting the ash-pits of the furnaces with the side flues in the floor of the kiln, and means for regulating the passage of the products of combustion, substantially as and for the purpose herein set forth.

4. In a downdraft brick-kiln, the structure having the side and end walls and the roof, the solid or imperforate floor having a central longitudinal flue or ditch, the chimneys rising from said ditch, and having draft-openings at their lower ends and dampers at their upper ends, the furnaces constructed transversely in the side walls and having open inner ends, and the fire-walls arranged parallel to and at a short distance from the side walls 75 of the kiln, substantially as and for the purpose set forth.

5. In a downdraft brick-kiln, the structure having the side and end walls and the roof, the solid or imperforate floor having longitudinal flues or ditches located parallel to and at a short distance from the side walls of the kiln, the ash-pits constructed under the furnaces transversely in said side walls and having flues connected with the longitudinal 85 ditches, the dampers at the outer ends of said flues, and the ventilators in the roof of the kiln, 90 substantially as and for the purpose set forth.

In testimony that I claim the foregoing as my own, I have hereto affixed my signature in presence of two witnesses.

PULASKI B. BROUGHTON.
